UNITED STATES PATENT OFFICE.

WILLIAM HIGGINS, OF CORBALLY, AND WILLIAM GEORGE EDMONDS, OF DUBLIN, IRELAND.

MACHINE OR APPARATUS FOR CORKING AND LABELING BOTTLES OR THE LIKE.

SPECIFICATION forming part of Letters Patent No. 745,840, dated December 1, 1903.

Application filed December 12, 1902. Serial No. 134,946. (No model.)

To all whom it may concern:

Be it known that we, WILLIAM HIGGINS, residing at Corbally Donamon post-office, Roscommon, in the county of Roscommon, and 5 WILLIAM GEORGE EDMONDS, residing at 9 Fownes street, in the city of Dublin, Ireland, subjects of the King of Great Britain, have invented a new and useful Machine or Apparatus for Corking and Labeling Bottles or the 10 Like, of which the following is a specification.

This invention relates to a machine or apparatus for simultaneously corking and applying labels to bottles and the like in one operation, thus both cheapening the cost of 15 apparatus for this purpose and at the same time economizing time.

According to the invention we make use of a corking-machine of known construction and of the kind wherein the bottle is held 20 upon a support and the cork is forced into the mouth thereof from a holder by means of a descending plunger operated by hand. In conjunction with this corking-machine we provide a labeling-machine preferably of the 25 kind described in the specification of our application of even date herewith, the said labeling-machine being actuated simultaneously with the operation of the corking-plunger, so as to paste the label and bring it against the 30 bottle as it is being corked.

To enable the invention to be fully understood, we will describe it by reference to the accompanying drawings, in which—

Figure 1 is a sectional front elevation of the 35 improved combined corking and labeling machine. Fig. 2 is an end elevation thereof. Fig. 3 is a sectional plan view, the section being on the line 3 3, Fig. 1; and Fig. 4 is a section on the line 4 4, Fig. 1.

40 *a* is the standard of the corking-machine; *b*, the bottle-support; *c*, the receptacle for the cork; *d*, the plunger for inserting the cork, and *e* the frame or slide, which is mounted in the support *a*, the said frame carrying the 45 plunger *d* and being reciprocated by the handle or lever *f*, which is pivoted to the support *a* at *f'* and is provided with a counter-weight *f''*. This handle operates the slide and also compresses the cork in the receptacle *c* in the well-known manner.

50 *g* is a bracket, which is bolted to the stand-

ard *a* and to which the labeling-machine is secured. This labeling-machine is, as hereinbefore mentioned, of the kind described in the specification of our application of even date herewith.

h represents the outer frame of the labeling-machine, *i* the label table or holder on which are held the pile of labels *i'*, and *j* is the frame, which is movably mounted inside the fixed frame *h* and within which the label table or holder *i* can also slide, being held in its outermost position with respect to the said frame *j* by the spring *k*, mounted upon the spindle *k'*.

l' is a weight attached to the frame *j* and which has for its object to withdraw the label-table from the pasting-pad, as hereinafter described.

In the machine described in the specification of our application of even date herewith the bottle or the like to be labeled is pushed upon the label-table; but in the arrangement herein shown, as the bottle must be fixed to be corked, it becomes necessary to advance 75 the label table or holder toward the bottle, this being effected simultaneously with the introduction of the cork into the neck of the bottle. To this end we proceed as follows:

The sliding frame *e*, which is directly operated by the hand-lever *f*, has pivoted to it a link *l*, this link being slotted, as shown at *l'*, at its lower end, the slotted portion engaging a pin *m* upon one end of a bell-crank lever *m'*, pivoted at *m* to the frame *h*, and the 80 other end of the said bell-crank lever being jointed, as shown at *m'*, to one end of a link *n*, the other end of which is pivoted to a pin *n'*, secured to a bar *n*², which slides in supports *n*³ *n*⁴, fixed upon the bracket *g*, and 85 which is designed to bear at its front end against the end of the frame *j* of the labeling-machine. With this arrangement it will be obvious that when the hand-lever *f* has been depressed for a certain distance the upper end 90 of the slot *l'* in the link *l* comes into contact with the pin *m* upon the bell-crank lever *m'* and turns the same upon its pivot, thus pushing forward the bar *n*², and thereby pressing forward the frame *j*, and consequently the label 95 table or holder *i*, against the bottle A at the moment that the cork is being inserted there-

in, the spring k enabling the table or holder i to yield to the necessary extent, and so cause the label to be curved in the manner described in the specification of our application 5 of even date herewith.

o is a frame carrying three pasting-pads o' , of corrugated rubber, which can be adjusted in position relatively with one another by means of the right and left hand screw o^2 , 10 working through nuts in the two outer pads, so as to enable the pad to paste labels of different dimensions. The frame o is supported on a reciprocating frame p , which is mounted in guides p' , and is attached at its upper 15 end to the lower end of a rack p^2 , gearing with a pinion p^3 , rotatably mounted on a stud p^4 in the main frame a and integral with or rigidly secured to a pinion q , gearing with a rack q' , connected to the sliding frame e . In 20 its normal position—that is to say, when the lever f is in its uppermost position, as shown in the drawings—the pile of labels is against the pasting-pad, and it will be obvious that the said pad must be removed from the 25 labels before the said labels are approached toward the bottle in the manner above described. This movement of the pasting-pad takes place during the lost movement of the link l , due to the slot l' , and it is effected 30 by the rack-and-pinion gear above described, which on the depression of the lever f forces down the frame p , this being done at a quicker rate than the frame e falls, as the pinion p^3 is of larger diameter than the pinion q . On 35 the downward movement of the frame p the frame o is caused to follow it by the springs o^3 o^4 , so as to enter the paste-container r . o^4 o^4 are springs coiled upon the ends of the frame-rods p p between the frame o and 40 the nuts o^5 upon the said rods. These springs yield when the frame o comes into contact with the guides p' p' , thereby allowing the frame p to move upward while the frame o and pad o' remain stationary as the labels are pressed 45 against and removed from the said pad.

To apply paste to the pad, we advantageously make use of the paste-container r , mounted upon the bracket g , and into which on the descent of the pad-support o a lip or 50 the like r' passes, so as to dip into the paste, and on the succeeding upward movement of the said support o carries up paste with it and applies it to a brush s , adjustably fixed, as clearly shown, in the bracket g . On the next 55 downward movement of the pasting-pads the paste is transformed from the brush to the pads and thence to the labels.

In order that the pasting-pad shall not be hindered in its up-and-down movement by 60 the clips for the labels which project from the said labels, we provide for slightly withdrawing the label-table at the beginning of the movement of the said pasting-pad to enable the latter to freely pass the label-clips. To 65 this end we pivot upon one of the brackets n^3 a lever t , one end of which bears against the

end of the frame j and the other end is hinged to a catch-arm t' , provided at its end with a claw t^2 , engaging the pin n' , which locks the bar n^2 to the arm n . This arm t when the 70 lever f is returned to its uppermost position (shown in Fig. 1) is caused by the lever m' , rod n , and arm t to force the frame j and label table or holder i forward beyond the end of the bar n^2 , as shown in Fig. 1, so as to apply 75 the labels against the pasting-pad. When now the lever f is depressed, the weight j' draws back the frame j and label table or holder until it meets the bar n^2 , which is simultaneously moved forward under the action 80 of the weight, and this movement of the frame j is sufficient to enable the pasting-pad to clear the label-clips. On the return upward movement of the lever f after labeling a bottle the frame j and label table or holder i are 85 pulled outward by the weight until the frame j bears equally against the rod t and bar n^2 , in which position it rests till the lower end of the slot l' engages the pin m , whereupon the rod t is caused to push the frame j forward 90 again into the position shown in Fig. 1.

Having now particularly described and ascertained the nature of our said invention and in what manner the same is to be performed, we declare that what we claim is—

95

1. In a label-affixing apparatus the combination with mechanism for holding the article to be labeled, in stationary position, of a reciprocating label-holder, provided with means for holding a plurality of superposed labels, and arranged to reciprocate in a path perpendicular to the face of the article to which the label is to be applied, and a reciprocating device, movable in a path perpendicular to the path of the label-holder, for applying paste to the outermost label thereon, substantially as described.

100

2. In a label-applying apparatus, the combination with mechanism for holding the article to be labeled of a reciprocating label-holder, provided with means for holding a plurality of superposed labels, and arranged to reciprocate in a path perpendicular to the face of the article to which the label is to be applied, a reciprocating pasting device movable in a path perpendicular to the path of the label-holder for applying paste to the outermost label and a stationary paste-applying device in the path of the pasting device, substantially as described.

110

3. In a label-affixing apparatus the combination with means for holding an article to be labeled, of a horizontally - reciprocating label-holder provided with means for holding a plurality of unpasted, superposed labels, said label-holder moving in a path perpendicular to the face of the article to which the label is to be applied, a pasting device, arranged to reciprocate vertically across the path of the label-holder to apply paste to the outermost label, a stationary paste-applying device located in the path of pasting device,

120

125

130

a paste-receptacle and means for supplying paste therefrom to the paste-applying device, substantially as described.

4. In a label-affixing apparatus, the combination with means for holding an article to be labeled, of a label-holder arranged to reciprocate horizontally toward and from the article, a paste-receptacle in a different horizontal plane from the label-holder, a vertically - reciprocating pasting - pad, provided with a paste-receiver adapted to enter said receptacle, a brush located in the path of said pasting-pad, and paste-receiver, for receiving paste from the latter and distributing it over the pasting device, substantially as described.

5. In a label-affixing apparatus, the combination with means for holding an article to be labeled of a reciprocating label - holder movable toward and from the article to be pasted, and provided with means for holding a plurality of superposed labels, a reciprocating pasting device, adapted to be brought into contact with the outermost label and movable in a path perpendicular to and across the path of the label-holder, means for adjusting the label-engaging face of said pasting device to correspond with the size of the label to be pasted, and a paste-applying device in the path of said pasting device, substantially as described.

6. In a label-affixing apparatus, the combination with means for holding an article to be labeled, of a label-holder arranged to reciprocate horizontally toward and from the article, a paste-receptacle in a different horizontal plane from the label-holder, a vertically - reciprocating pasting - pad, formed of sections and adjustable to paste labels of varying sizes, a paste-receiver connected therewith and adapted to enter said receptacle, and a stationary brush in the path formed of said pad and receiver, substantially as described.

7. In a label-affixing apparatus, the combination with means for holding an article to

be labeled, of a label-holder arranged to reciprocate horizontally toward and from the article, a paste-receptacle in a different horizontal plane from the label-holder, a vertically-reciprocating pasting - pad, adapted to receive paste from said receptacle and apply it to the labels on said holder, and mechanism for withdrawing said holder, from engagement with said pad before applying a label to allow the pasting-pad to move out of the path of said holder, substantially as described.

8. In a corking and labeling apparatus, the combination with mechanism for holding the bottle, of corking mechanism, a reciprocating label-holder provided with means for holding a plurality of superposed labels and arranged to reciprocate in a path perpendicular to the face of the bottle, a reciprocating device movable in a path perpendicular to the path of the label-holder, for applying paste to the outermost label a single operating-lever, and connections between said lever and said corking device, label - table and reciprocating paste - applying device, substantially as described.

9. The combination with devices for holding a bottle, of a reciprocating label-holder, adapted to move toward and from the bottle in a path perpendicular to the face thereof to which the label is to be applied, pasting mechanism for the labels, corking mechanism movable in a plane perpendicular to the path of the label-holder, a single operating-lever, connections between said corking mechanism and said lever, and operative connections providing for lost motion between the said lever and said label-holder, substantially as described.
